Joseph Pratt of Boston, Mass.
Letter Patent No. 361. Dated March 25, 1851.

The Schedule referred to in these Letters Patent and making part of the same.

To all Persons to whom these Presents shall come:

Be it known,

that I, Joseph Pratt, of Boston, in the County of Suffolk and State of Massachusetts, have invented or produced, a new design for the top, front, and bottom of a parlor grate, and I do hereby declare that the said new design is fully described and represented, in the following specification and accompanying drawings, to which reference is herein after made.

Fig. 1. Plate 1, is a front view of the said grate. Fig. 2, plate 2, is a top view of the same. Fig. 3, plate 3, is a vertical section, taken in the plane of the line A. B. Fig. 1, pl. 1, and Fig. 2, pl. 2, showing the contour of the mouldings.

My new design is as follows: Around

2

the exterior of the hearth plate is the beaded moulding a,a,a within which is the concave moulding b,b,b, ornamented with the series of semi-prismoidal picket heads c,c,c &c. connected by the crescent sweeps d,d,d, and all cast in bas-relief, as shown in the several drawings. Within the moulding is the plain raised moulding e,e,e, and this completes the description of the ornaments on the hearth plate. The movable ash-plate is ornamented by having the concave top f,f, formed with the converging grooves g,g,g,g, and is surrounded by the plain raised moulding h,h,h, and the concave moulding i,i,i, having the curved or rounded picket heads k,k,k, cast thereon, is bas-relief, and connected together by the curved beaded work l,l,l,&c.

The front plate of the grate is formed on the side with the console shaped mouldings m,m,&m,m, which are supported on the plinth blocks n,n, and surmounted by caps and horizontal moulding p,p. Around the top of the opening of the grate is the elliptical arched moulding q,q, supported on the fluted pilasters r,r,-r,r, having proper bases and capitals a,l,s,-s,t, respectively. Directly over the centre of the arch is the roselle u, cast in bas-relief, in the sunken circular panel, while two smaller rosettes w,w, are similarly cast over the capitals t,t. Between the exterior moulding m,m,&c. and the pilasters r,r,&c. are the several sunken-panels x,x,&q,q, of the irregular shape shown in fig. 1, pl. 1.

The top of the grate is formed with a sunken, elongated panel q,q; having rosettes r,r,r,r, at each corner having two picket heads connected together by the ornamental connecting brace, all cast in bas-relief on said panel.

The blower is cast with two sunken panels s,s,-s,s, having three Norman arches at the top, with enriched pendants t,t, cast in bas-relief.

The top plate is of the shape shown at a,a,a, and is surrounded by the ogee moulding x, having the straight leaves b,b,&c., with circular ends, each ornamented with the semi-spheres c,c, and elongated ribs d,d, cast in bas-relief, as shown in Fig. 2, pl. 2.

There is a raised elliptical surface, surrounded by a concave moulding e', e', e' , having a series of sunken ellipses f', f', f' . There is a circular movable plate g', g' , with a series of spear heads h', h', h' , cast in bas-relief, and converging towards the centre, and connected by the crescent sweeps i', i', i' . On each side of this circular plate is the semi-elliptical ornamented space k', k', k' - k', k', k' , having a circular space l' at the centre, and radial grooves $m', m', \&c.$, running from said space l' to the edge of the spaces k', k', k' &c. On each side of the raised elliptical surface e', e', e' , is a three sided area $n', n', n' - n', n', n'$, two of the sides being curved, so as to conform to the curve of the surface e', e', e' , and that of the back of the top plate, the said areas being filled with the radial ribs $o', o', o', \&c.$, proceeding from a raised circle p', p' , at the centre.

Having thus described my new design, I shall state my claim as follows:

What I claim as my production & design to have secured to me by Letters Patent, is the several ornamented mouldings round the hearth plate ash pan, and front and top plates, above described and represented in the drawings, with the ornaments above specified and shown in the several drawings, as cast on the front and top plate, and blower and top of the grate, forming a new design for a parlor grate.
